CONTROL DEVICE

William A. Ray, Glendale, Calif.

Application June 25, 1941, Serial No. 399,600

5 Claims. (Cl. 200—138)

My present invention relates to control devices and particularly to those of the thermally responsive type. It is well known that, in a space wherein fluid is circulating, the distribution of heat is never uniform. Not only is the temperature at various points in the space different, but also the temperature difference between the points may vary considerably with variation of fluid circulation. Thus, when a plurality of thermally responsive devices, the settings of which should be proportional, are located at various points, their respective responses under varying conditions of fluid circulation will vary. This effect is particularly noticeable in the bonnet of a hot-air furnace wherein the distribution of heat is greatly affected by the opening or closing of the hot-air ducts and by change of air circulation in the spaces heated by the furnace. It is therefore a general object of my invention to provide a unitary temperature control device comprising a plurality of thermally responsive elements which are so intimately arranged with respect to each other that the temperature of the various elements is always substantially the same.

Another object of my invention is the provision of a control device, particularly adapted for use in the bonnet of a hot-air furnace, which comprises a pair of elongated thermally responsive elements, one of which encircles a substantial portion of the other.

Another object is the provision of a control device of the type indicated in the preceding object wherein one of the thermally responsive elements is of metal (bimetal or expansion-rod type) and the other of the fluid-expansion type which, while not as permanently reliable as the metallic type on account of possible eventual leakage of fluid, provides more power per unit of heat-collecting area.

Other objects and advantages of the invention will be found in the description, the drawing, and the appended claims.

For complete understanding of the invention, reference may be had to the following detailed description and accompanying drawing, wherein:

Figure 1 is a longitudinal sectional view of a control device embodying my invention; and

Figure 2 is a diagrammatic view of a hot-air heating system including the device shown in Fig. 1.

Referring first to Fig. 1 of the drawing, the numeral 11 indicates a casing or base member having a flange 12 for attachment to the wall of a

heating device. The central portion of the vertical wall of the casing is thickened to provide a boss 13, to a reduced outer portion of which is secured one end of a spirally-wound bimetallic strip 14. The other or outer end of the bimetallic strip is secured to a centrally located rod 15, the inner-end portion of which extends through and is guided in an opening in the boss 13 and casing wall. To the end of rod 15 within the casing is secured a cam 16, upon the surface of which one end of a flexible metallic contact strip 17 constantly bears, the other end of the strip being secured to a terminal 18 insulatingly mounted in the upper wall of the casing. Connected to a similar terminal 19 is another contact strip 20, the bent lower end of which is normally in engagement with contact strip 17.

Sealingly mounted in a passage 21 in the boss 13 is the inner open end of a spirally-wound tubular member or coil 22 which encircles a substantial portion of the bimetallic member 14. The sealed outer end of the coil is supported in a bracket 23 attached to a perforated cylindrical guard housing 24 carried by the boss 13. The passage 21 communicates with a recess 25 formed in the underside of the thickened bottom wall of the casing, covering which recess is a flexible diaphragm 26, secured at its margin to the undersurface of the casing by a housing 27. The tubular member 22 and the recess 25 are charged with a thermally-expansible fluid; the fluid pressure system being either of the hydraulic or vapor-tension type, whichever is more suitable to the particular conditions under which the device is to be employed. Carried by the central portion of the diaphragm is a contact plate 28 which, when the diaphragm is forced downward by fluid pressure in the recess 25, is adapted to bridge the heads of contact screws 29, insulatingly mounted in the bottom wall of housing 27; a compression spring 30 urging the diaphragm and contact plate upward. Closing the open end of casing 11 is a cover plate 31.

Referring now to the diagram of Fig. 2, the numeral 40 indicates the outer wall of a hot-air furnace which includes a central heating unit or stove 41 wherein is located a main gas burner 42. This burner is supplied with fuel by a conduit 43 wherein is connected a main valve casing 50 44, flow through which is controlled by a diaphragm-carried closure 45. Gas pressure on the diaphragm for actuating the closure is controlled by an electrically operated pilot valve, generally indicated at 46, in a manner well known in the art.

The air heated by the stove 41 is supplied by an electrically operated fan 47, mounted in an inlet duct 48, to a space or room 49 through an outlet duct 50. Outlet ducts for supplying other rooms are indicated at 51 and 52. Mounted in the room 49 is a thermostat 53 which controls the energization of pilot valve 46 in accordance with the heating requirements of the room. This thermostat is connected by wires 54 to the pilot valve in series with terminals 18 and 19 of the control device shown in Fig. 1 and a thermoelectric device 55 which is heated by the flame of a pilot burner 56 provided for the ignition of the main burner and connected to the gas supply ahead of the main burner valve. The thermoelectric device 55, preferably composed of a plurality of thermocouples connected in series, is employed as a convenient source of power, which power is ample for the energization of pilot valve 46, and has an additional advantage in that, upon accidental extinction of the pilot burner flame, the resultant cessation of current effects closure of the main burner valve. The fan 47 is connected by wires 57 to any suitable source of electrical energy in series with terminals 29 of the fluid pressure operated switch of the control device shown in Fig. 1.

The operation of the heating system is as follows: When the temperature in the room falls to a point at which heat is demanded, the thermostat 53 completes the electrical circuit between the pilot valve 46 and the source of energy 55, the contacts 17 and 20 actuated by the bimetallic member 14 being normally closed, with the result that fuel is supplied to the main burner where it is ignited by the continuously burning flame of the pilot burner 56. Upon sufficient rise of temperature in the furnace bonnet, the fluid in coil 22 expands, closing contacts 29, and the fan 47 is operated to circulate the heated air to the room. When the demand for heat is satisfied, the room thermostat acts to close fuel supply to the main burner, the fan continuing to operate until the bonnet temperature reaches a low point at which the fluid pressure operated switch contacts open. In the event of abnormal rise in bonnet temperature, such as might be occasioned by the closing of one or more of the hot-air ducts, the bimetallic coil 14 expands to such an extent that its cam is rotated to a position in which contacts 17 and 20 are open. When this occurs, due to the resultant deenergization of pilot valve 46, fuel supply to the main burner is stopped until the bonnet temperature falls to a safe low degree.

As was pointed out in the statement of invention, the thermally responsive elements 14 and 22 are so intimately arranged that they are always substantially at the same respective temperature and therefore maintain their adjusted ratio of response. If the elements were located at different points in the furnace bonnet—spaced even only an inch or so apart—this ratio would not be maintained with variation of furnace conditions and fluid circulation in the bonnet (caused, for example, by the opening or closing of one or more of the hot-air ducts) which would affect one element to a greater degree than the other. As was brought out above in the final object, it is preferred to employ a thermostat of the fluid-expansion type for the control of the circulating fan on account of its greater flexibility and capability of producing more power per unit of heat-collecting area, while the more

reliable bimetallic or expansion-rod type of thermostat is preferred as a high-limit control.

While I have herein shown and described a specific form of my invention and its application to the control of a hot-air furnace, it is obvious that the device shown is subject to modification without departing from the spirit of the invention and is applicable to the control of other systems. I intend therefore to be limited only by the scope of the appended claims.

I claim as my invention:

1. In a dual device for controlling the operation of temperature changing means: a pair of thermostatic elements adapted to be subjected to the temperature of a flowing circumambient medium, one of the elements being surrounded by the other to form an outer and an inner element, said outer element being arranged in such manner as to provide a free opening to the inner element, said opening being so arranged that the circumambient medium substantially uniformly affects the elements in any direction of flow thereof, and independent switching means actuated by each of the elements.

2. In a dual device for controlling the operation of temperature changing means: a pair of thermostatic elements adapted to be subjected to the temperature of a flowing circumambient medium, one of said elements being coiled around the other to form an inner and an outer element, the coils of said outer element being spaced apart to permit free circulation of the circumambient medium to the inner element so that both of the elements are substantially uniformly effected by flow of the medium in any direction, and independent switching means actuated by each of the elements.

3. In a dual device for controlling the operation of temperature changing means: a pair of thermostatic elements adapted to be subjected to the temperature of a flowing circumambient medium, one of said elements being in the form of an elongated thermally expansible metallic member, the other of said elements being in the form of an elongated hollow member containing a thermally expansible fluid, one of the elements being surrounded by the other to form an outer and an inner element, said outer element being arranged in such manner as to provide a free opening to the inner element, said opening being so arranged that the circumambient medium substantially uniformly affects the elements in any direction of flow thereof, and independent switching means actuated by each of the elements.

4. In a dual device for controlling the operation of temperature changing means: a base member, a pair of thermostatic elements extending from said base member at one side thereof and adapted to be subjected to the temperature of a flowing medium circumambient the elements, one of said elements consisting of an elongated thermally expansible metallic member, the other of said elements consisting of an elongated hollow member containing a thermally expansible fluid, one of the elements being coiled around the other in spaced relation thereto to form an inner and an outer element, the coils of said outer element being spaced apart to permit free circulation of said medium to the inner element so that both of the elements are substantially uniformly affected by flow of the medium in any direction, switching means mounted on said base member and actuated by the expansion of said metallic member, and ad-

ditional switching means also mounted on said base member and actuated by the expansion of said fluid.

5. In a dual device for controlling the operation of temperature changing means: a base member, a pair of thermostatic elements extending from said base member at one side thereof and adapted to be subjected to the temperature of a flowing medium circumambient the elements, one of said elements consisting of an elongated thermally expansible metallic member, the other of said elements consisting of an elongated hollow member containing a thermally expansible fluid, said hollow member being coiled

around said metallic member in spaced relation thereto to form an inner and an outer element, the coils of said outer element being spaced apart to permit free circulation of said medium to the inner element so that both of the elements are substantially uniformly affected by flow of the medium in any direction, switching means mounted on said base member and actuated by the expansion of said metallic member, and additional switching means also mounted on said base member and actuated by the expansion of said fluid.

WILLIAM A. RAY.
